UNITED STATES PATENT OFFICE.

GUSTAVE LIDSEEN, OF CHICAGO, ILLINOIS.

OIL CAN.

Application filed November 25, 1921. Serial No. 517,456.

To all whom it may concern:

Be it known that I, GUSTAVE LIDSEEN, a citizen of the United States, and a resident of the city of Chicago, in the county of Cook and State of Illinois, have invented certain new and useful Improvements in an Oil Can; and I do hereby declare that the following is a full, clear, and exact description of the same, reference being had to the accompanying drawings, and to the numerals of reference marked thereon, which form a part of this specification.

This invention relates to an improved type of textile oiler or oil can, constructed to emit small quantities of thin oil through a spring controlled valve located at the outer end of the spout and adapted to be actuated by a force pump mechanism operable by a lever.

It is an object of this invention to provide an oil can constructed to eject drops or small quantities of oil from a valve controlled spout.

It is also an object of the invention to provide an oil can having a valve in the spout thereof adapted to be automatically closed to prevent leakage of oil from the can should the can be accidentally overturned.

It is a further object of this invention to provide an oil can, the cover of which is equipped with an operating lever which when operated, when the can is inverted, acts to cause oil to be forced by pressure through a spring controlled valve into the outer portion of the spout and then through a spring controlled outlet valve controlling the outer end of said spout.

It is furthermore an object of the invention to provide a spout cover for an oil can wherein the spout has a plurality of spring controlled valves therein adapted to be opened by a lever mechanism mounted on the cover.

Another object of the invention is to provide an oil can, the spout of which is provided with a pressure operated valve adapted to permit small quantities of oil to be forced therethrough to be emitted through a valve in the end of the spout, said spout valve adapted to be opened by operating a lever.

It is an important object of this invention to provide an oil can of simple and effective construction adapted particularly for emitting small quantities of thin oil successively through valve mechanisms mounted within the oil can spout and operable by means of a lever mechanism.

Other and further important objects of this invention will be apparent from the disclosures in the drawings and specification.

The invention (in a preferred form) is illustrated on the drawings and hereinafter more fully described.

On the drawings:

Figure 1 is a vertical section taken centrally through an oil can embodying the principles of this invention showing parts in elevation.

Figure 2 is a similar section showing the spout valve in open position and with the lever depressed.

Figure 3 is an enlarged detail view taken on line 3-3 of Figure 1.

Figure 4 is an enlarged detail side view of the lever showing parts in section.

As shown on the drawings:

The reference numeral 1 indicates a can or container having an integral neck 2. Rigidly secured within the neck 2 is a collar 3, having an integral outwardly directed flange 4.

Removably engaged on the can 1 is a spout cap comprising a cover 5, the margin of which is bent to form a rim 6 adapted to be removably engaged on the can flange 4. A gasket or packing ring 7 is provided in the cover rim 6 to form a tight joint between the can flange 4 and the cover 5. Integrally formed on the cover 5 is a cylindrical shell or casing 8 having rigidly secured therein by soldering or other suitable means the lower enlarged end of a tapered oil spout 9.

Projecting longitudinally through the spout 9 and the shell 8 is a valve stem 10 having an outlet valve head 11 formed on the outer end thereof adapted to seat in the end of the spout to close the same. Secured on the lower or inner end of the valve stem 10 is a stop or clip 12 against which the lower or inner end of a coiled spring 13 seats. The spring 13 is wound around the lower portion of the valve stem 10 and has the upper end pressing against the bottom of a check valve plate 14. The check valve plate has outlet apertures 15 therein and a middle opening through which the valve stem 10 projects. The check valve plate 14 is provided with an integral upwardly directed rim or flange 16 which contacts the inner surface of the spout shell 8 and abuts against the lower or inner end of the spout 9. Seated on the check valve plate 14 is a valve disk 17 having a central opening

through which the valve stem 10 projects. A washer or clip 18 is secured on the valve stem above the valve disk 17. A coiled spring 19 is disposed within the shell 8. The 5 lower end of the coiled spring 19 seats against the flexible valve disk 17 while the upper end of said spring engages against the inner inclined surface of the lower end of the spout 9 as illustrated in Figures 1 and 10 2. Engaged in the shell 8 below the valve plate 14 is a large coiled spring 20 the upper end of which seats against the bottom of the check valve plate 14 while the lower end of said spring 20 seats in a cup or plunger 15 21. The plunger 21 is slidably disposed within the lower or inner end of the cover shell 8 and has portions thereof cut away to afford inlet openings 22.

To hold the oil ejecting cup 21 in position 20 to permit actuation of the same, the inner curved end 23 of an actuating or supporting arm 24 contacts with the bottom surface of said plunger 21. The outer end of the arm 24 projects through a spring washer 25 plate 25 and through a slot 26 provided in an indented portion or socket 27 formed in the cover 5. Movably seated within the socket 27 to cover the slot 26 and afford a non-leaking joint, is a curved washer plate 30 28 having an aperture therein through which the outer end of the arm 24 projects. Integrally formed on the projecting end of the arm 24 is a finger piece or lever 29. A portion of the lever 29 where it joins the 35 arm 24 is curved as at 30 and is rigidly secured to the washer plate 28. To hold the washer 28 and the curved portion 30 of the lever seated in the socket 27, a retaining member 31 is engaged on the arm 24, said 40 member comprising a curved shank having a head 32 formed on one end and retaining lugs or clips 33 integrally formed on the other end and which are bent to engage around the arm 24 to hold the retaining member in place. The head 32 of the 45 retaining member is forced against the spring washer plate 25 and forces the same from the dotted line position of Figure 4 to the full line position, thereby making the washer plate conform to the curvatures of the socket 27 and thus prevent leakage through the opening 26. The spring washer plate 50 also acts, in conjunction with said member 31, to hold the washer plate 28 and the curved portion 30 of the lever seated within the cover socket.

The operation is as follows:

The oil can is adapted to be filled with oil by removing the spout cover. The spout 60 cover is then locked to the can 1 by friction retaining mechanisms similar to the construction disclosed in Letters Patent No. 1,401,160, granted to me December 27, 1921, for improvements in lubricating cans.

65 Normally, the actuating lever 29 is held

in an elevated position, as shown in Figure 1, by the action of the coiled spring 20 which forces the plunger 21 downwardly against the inner curved end 23 of the lever mechanism. The small coiled spring 13 acting against the clip 12 holds the outlet valve 11 seated in the outer end of the spout 9 to close the same. The check valve control spring 19 acts to hold the flexible valve disk 17 seated flat upon the apertured check valve plate 14 to close the apertures 15. With check valve and the outlet valve closed, leakage of oil from the spout 9 is prevented should the oil can be accidentally over-turned or left lying on its side.

To use the oil can, the same is turned to one side or inverted with the mouth of the spout 9 engaged in or upon a device or mechanism requiring lubrication. The oil in the can is thus permitted to flow through the 85 openings 22 into the plunger 21 and into the chamber within the shell 8. The lever 29 is now depressed thereby rotating or moving the washers 25 and 28 with respect to the cover socket 27 and at the same time causing 90 the arm 24 to move in the slot 26. The inner end 23 of the arm 24 is thus swung upwardly, thereby forcing the plunger 21 into the shell 8. Inward movement of the plunger causes oil to be trapped therein and also 95 causes compression of the plunger control spring 20.

As the plunger moves outwardly or into the shell 8, the trapped oil being under pressure is forced through the check valve openings 15, thereby slightly lifting the check valve disk 17 against the action of the check valve spring 19. A small quantity of oil is thus forced into the spout 9 and flows outwardly toward the mouth of the spout 9. With the movement of the plunger into the shell 8, the bottom of said plunger is brought into contact with the inner end of the outlet valve stem 10 and forces the same outwardly compressing the spring 13 and opening the valve 11. Oil in the spout 9 is thus permitted to flow by gravity from the mouth of said spout.

When the lever 29 is released, the spring 20 returns the plunger 21 from the position shown in Figure 2 to normal position, thereby also causing the lever mechanism to be returned to the normal position illustrated in Figure 1. The spring 13 acts automatically to pull the valve stem 10 inwardly, thereby closing the discharge valve 11. The check valve disk 17 is closed by the spring 19, thereby closing the apertures 15 in the check valve plate 14.

In the textile business, it is necessary to 125 use an oil can adapted to emit small quantities of very thin oil. The check valve mechanism within the enlarged lower portion of the spout permits only small quantities of oil to pass therethrough into the 130

outer portion of the spout 9 to be emitted through the outlet or discharge valve 11.

I am aware that numerous details of construction may be varied through a wide range without departing from the principles of this invention, and I therefore do not purpose limiting the patent granted otherwise than necessitated by the prior art.

I claim as my invention:

10. 1. The combination with an oil can spout, of an outlet valve therein, a check valve therein, and means for forcing a limited quantity of oil past said check valve and opening said outlet valve, whereby the oil fed past said check valve may discharge by gravity.

2. The combination with an oil can spout, of means for trapping oil therein, a check valve in said spout, a discharge valve in said spout to the outside of said check valve, and means for actuating said oil trapping means to cause the same to force oil through the check valve and to open the discharge valve to permit flow 25 of oil from the spout.

3. An oil can, comprising an oil container, a spout removably engaged thereon, a spring controlled plunger in said spout, a lever mechanism on said spout adapted to 30 operate said plunger, a check valve in said spout adapted to have oil forced therethrough when the plunger is actuated initially, and a discharge valve in said spout adapted to be operated by further movement of said plunger to permit oil 35 passing through the check valve to be discharged from said spout.

4. An oil can, comprising an oil container, a cover removably engaged thereon, a spout 40 rigidly secured to said cover, a lever mechanism on said cover and projecting into said container, an apertured plunger in said spout resting on the inner end of said lever mechanism, a spring in said plunger 45 to hold the plunger in contact with said lever mechanism and further acting to hold the lever mechanism in normal operating position, a check valve in said spout above the plunger, a spring controlling said check 50 valve, a discharge valve in the outer end of said spout, a valve stem connected thereto and projecting into said plunger to be actuated thereby, and a spring on said valve stem for normally holding the discharge 55 valve in closed position.

5. An oil can, comprising an oil container, a spout thereon, oil ejecting means in said spout, a lever for operating the same, a check valve in said spout, and a discharge

valve in said spout, said discharge valve 60 adapted to be opened by said ejecting means when the same is operated by said lever, and said check valve adapted to be opened by the pressure of oil ejected.

6. An oil can, comprising an oil container, 65 a spout removably engaged thereon, oil ejecting means in said spout having openings therein to permit oil from the container to flow into the spout when the oil can is inverted, a check valve in said spout to the outside of said oil ejecting means, a discharge valve in the outer end of said spout, and a mechanism supported on said spout for forcing said oil ejecting means into the spout to force small quantities of oil 70 through said check valve and to cause said oil ejecting means to open the discharge valve to permit the escape of the oil passing through the check valve.

7. An oil can, comprising an oil container, 80 a spout cover removably engaged thereon, a discharge valve in said spout cover, a check valve also provided in said spout cover, and an oil ejecting means in said spout cover adapted to cause operation 85 of both the check valve and said discharge valve to permit oil to flow from the oil can.

8. The combination with an oil can spout, of a discharge valve in one end thereof, 90 an oil ejecting means slidable in the other end of said spout, and a check valve in said spout between the discharge valve and said oil ejecting means.

9. In an oil can of the class described, 95 the combination with a container, a cover removably engaged thereon, a socket formed therein, a curved washer plate movably seated in said socket to form a non-leaking joint, a lever projecting through 100 said curved washer plate and rigidly secured thereto, a spring washer plate on the inner portion of the lever adjacent the inner surface of the socket, a retaining member clamped on the inner portion of 105 said lever adapted to tension the spring washer plate seated in said socket, and oil ejecting means in said cover adapted to be actuated by said lever.

In testimony whereof I have hereunto 110 subscribed my name in the presence of two subscribing witnesses.

GUSTAVE LIDSEEN.
